UNITED STATES PATENT OFFICE.

ROBERT H. BERKSTRESSER, OF YORK, PENNSYLVANIA.

TIME-CONTROLLED MECHANISM.

1,337,037.

Specification of Letters Patent.

Patented Apr. 13, 1920.

Application filed January 9, 1918. Serial No. 211,005.

To all whom it may concern:

Be it known that I, ROBERT H. BERKSTRESSER, a citizen of the United States, residing at York, in the county of York and State 5 of Pennsylvania, have invented certain new and useful Improvements in Time-Controlled Mechanism, of which the following is a specification.

My present invention pertains to time- 10 controlled mechanism for throwing off electric switches, effecting the movement of furnace dampers, and accomplishing other purposes to which it is applicable at predetermined times.

15 The general object of the invention is the provision of a time controlled mechanism, of the character set forth, constructed in such manner that it is simple and inexpensive, is reliable in action, is easily set 20 and without liability of premature casual operation, and is well adapted to withstand the rough usage and exposure to which such mechanism is ordinarily subjected particularly when located in cellars where dust 25 and dirt as well as dampness are to be found.

With the foregoing in mind, the invention will be fully understood from the following description and claim when the same are considered in connection with the drawings, accompanying and forming part of 30 this specification, in which:

Figure 1 is a side elevation of my novel time-controlled mechanism as the same appears when set to operate at a predetermined 35 time.

Fig. 2 is a corresponding view with the several working parts in the positions they assume after an operation of the mechanism.

40 Fig. 3 is a front elevation showing the mechanism as set.

Fig. 4 is a horizontal section, taken in the plane indicated by the line 4—4 of Fig. 3, looking downwardly.

45 Fig. 5 is a detail view, on an enlarged scale, showing the set engagement between the arm on the rock shaft that carries the swinging wing, and the lever which when properly engaged prevents movement of the 50 swinging wing under the action of the retractile spring connected thereto.

Similar numerals of reference designate corresponding parts in all the views of the drawings.

55 Among other elements my novel time-controlled mechanism comprises a support

which may be of the type illustrated or of any other construction compatible with the purpose of my invention.

On a horizontal bracket 2 carried by said 60 support is arranged and suitably secured an alarm or other clock 3 adapted to be set so that at predetermined time a movable element, a bell clapper 4 for instance, will be actuated. The clock 3 *per se* is not of my 65 invention, and I would therefore have it understood that any time device capable of being set to actuate a movable element such as 4 at a predetermined time may be employed without affecting my invention. 70

Opposed to and adapted to be moved by the movable time-controlled element 4 is one arm of a suitably supported bell crank 5, the other arm of which is connected through a link rod 6 with one arm of what 75 I will hereinafter denominate a trigger lever 7. The said trigger lever 7 is pivoted at 8 to a bracket 9 on one of a pair of spaced standards 10 and 11 that are fixed to and project from the face of the support first 80 mentioned. It will be noticed here that the other or outer arm of the said trigger lever 7 is somewhat beveled for a purpose hereinafter set forth.

Journalized in the standards 10 and 11 is 85 a rock shaft 12, and fixed to and projecting from said rock shaft 12 is an arm 13, having at its free end a bib 14 on which is a projection 15, designed and adapted to engage with the beveled end of the trigger lever 90 7, after the manner shown in Figs. 1 and 5, and this with a view to precluding casual release of the arm 13 from the trigger lever 7 while permitting free release when the predetermined time arrives, which is a 95 desideratum in time-controlled mechanisms.

Also fixed to the rock shaft 12 and arranged between the standards 10 and 11 is the wing 16 of my improvement. This wing 100 16 has a tail 17, disposed at the opposite side of the rock shaft, with reference to the wing, as illustrated. The wing also has one or more apertures disposed adjacent to its free end; the said apertures being numbered 19, and being designed for the convenient 105 attachment of connecting devices 20, adapted to effect connection between the wing and the electric or other switches, the dampers or other devices to be moved when the wing 110 16 is powerfully swung on its axis by its complementary spring 21.

The spring 21 is of the retractile type as

illustrated, in the preferred embodiment of my invention, and is connected at one of its ends to the tail 17 of the wing 16, and at its opposite end, by preference, to a tension regulating device 22, preferably in the form of a slotted bar, connected by screws 23 that extend through its slots 24 to the support first mentioned, so that the tension of the spring 21 may be readily regulated by loosening the screws, adjusting the bar lengthwise, and then re-tightening the screws.

The practical and reliable character of my novel time-controlled mechanism will be fully appreciated from the foregoing.

In operation, the wing 16 coupled to one or more connecting devices 20 is swung with the rock shaft 12 from the position shown in Fig. 2 to that shown in Fig. 1 so as to place the notched portion or the projection on the bib of the rock-shaft arm over and in engagement with the beveled end of the trigger lever 7, Fig. 1. The stated swinging of the lever 16 places the retractile spring under tension and from this it follows that on the release of the rock-shaft arm from the trigger lever the spring will powerfully swing the wing in the opposite direction with the result that the wing will strongly pull on the connecting device or devices attached to it. The stated release of the rock-shaft arm from the trigger lever is accomplished at a predetermined time by the bell crank being moved by the element 4 of the clock or time device.

At 25 on the support first mentioned is a buffer of rubber or other suitable material, arranged to receive the impact of the wing when the latter is powerfully moved by the contraction of its complementary spring this with a view to preventing the operation of the mechanism from injuring any of the parts comprised therein.

Particular attention is called to the fact that the spring 21 is so arranged with respect to the wing, that it will oppose the movement of the wing, in either direction, when thrown to the most forward position. The spring therefor opposes the oscillatory

movements of the wing and causes the same to quickly come to rest and will frequently stop its movement before it contacts with the member 25.

Having described my invention, what I claim and desire to secure by Letters Patent is:

The combination with a support, of supporting brackets secured thereto in spaced relation and arranged at substantially a right angle with relation thereto, a rock shaft connected with the ends of the brackets and spaced from the support and arranged substantially parallel therewith, an operating member carried by the rock shaft and having short and long end portions projecting upon opposite sides of the rock shaft, the short end portion being adapted to swing between the rock shaft and the support, and the long end portion being arranged to swing entirely upon the outer side of the rock shaft, pull element or elements secured to the long end portion, a retractile coil spring secured to the short end portion and adapted to project between the rock shaft and the support when the operating member is in the cocked position, a longitudinally adjustable element carried by the support and connected with the free end of the spring for regulating its tension, with the spring disposed substantially parallel with the adjustable element when the operating member is cocked, a crank rigidly secured to the rock shaft and extending in the direction of the short end portion and adapted to swing between the rock shaft and the support, a trigger lever connected with the support and adapted to engage with the free end of the crank and disposed at substantially a right angle thereto when the operating member is cocked, and time-controlled means to move the trigger lever.

In testimony whereof I affix my signature in presence of two witnesses.

ROBERT H. BERKSTRESSER.

Witnesses:

R. E. GOODLING,

MARTHA J. ROFFENSBERGER.
